LOOP INDUCTANCE COMPENSATOR

Stanley Cutler and Norton Wiener, Los Angeles,
Calif., assignors to Hoffman Radio Corpora-
tion, a corporation of California

Application October 30, 1946, Serial No. 706,668

4 Claims. (Cl. 250—33.67)

1

This invention relates to radio equipment, particularly to loop antenna arrangements for use with portable radio receiving or transmitting equipment.

Portable radio apparatus, and particularly portable radio receivers, are often provided with a loop antenna which may be used in either of two positions, namely folded within the cabinet, or, where increased pickup sensitivity is required, in a position extending outside the cabinet. When such a loop is operated in its position inside the cabinet of the apparatus, it is generally in close proximity to the receiver chassis or other metal parts, while if the cabinet is of metal and the door to the antenna is made of insulating material to increase the sensitivity when the antenna is used internally, the metallic cabinet material around the door opening acts as a shorted turn coupled to the loop. In either case, the antenna suffers a decrease of inductance, and the antenna circuit is detuned with a consequent loss of sensitivity and selectivity, as compared with conditions when the loop is operated in its outboard position.

It is an object of the present invention to overcome the variation in antenna inductance resulting from its movement between the two positions described above, whereby regardless of the position of the antenna, the circuits of the apparatus are operated at optimum sensitivity and selectivity. A further object is to accomplish the compensation for the changing relation of antenna to adjacent materials in a completely automatic manner, whereby the desired compensation is effected without the necessity of any conscious action on the part of the user in adjusting the antenna. A still further object is to provide a means for achieving the above results without complication of existing designs of cabinets or antennas, and in a very simple and economical manner.

An ancillary object of the invention is to provide for the compensation indicated above in such a manner that minor adjustments of the degree of compensation may be accomplished very simply, to take care of possible production variations in the relationships of antennas to the other parts of the apparatus.

A still further object is to accomplish the above results without adversely affecting the "Q" of the antenna to any appreciable extent. As pointed out below, under some circumstances the effective "Q" of the antenna may actually be increased over that of an uncompensated antenna.

The above and other objects and advantages of

2

the invention will best be understood by reference to the following description of certain specific embodiments of our invention, taken in connection with the accompanying drawings, in which:

Fig. 1 is a side elevational view of a portable radio receiver cabinet provided with our invention, the antenna being in extended position.

Fig. 2 is a plan view of the same.

Fig. 3 is a view similar to Fig. 1 but with the antenna in its closed position, parts being shown in section, and

Fig. 4 is a view similar to Fig. 2 but showing a slightly modified form of antenna compensating slug.

Referring now to Fig. 1 of the drawings, there is shown a radio receiver cabinet 10 of usual construction, provided with a hinged door 12 giving access to a loop antenna 14 hingedly mounted on said door. The cabinet 10 may be of metal or of some insulating material, such as wood, but in either event the door 12 will usually be of an insulating material in order to increase the signal pick-up when the antenna is in its closed position. It will be observed that when the antenna 14 is in the full-line position of Fig. 1, it is spaced some distance from the cabinet 10, and hence operates essentially in free space. When however, such an antenna is moved to its closed position within the cabinet 10, as indicated in Fig. 3, its inductance is decreased due to its proximity to the metal parts of the chassis 13, or to the metal surrounding the opening of door 12, so that the inductance of the antenna is no longer properly matched to the tuned circuits of the equipment.

In order to overcome the above undesirable change in the properties of the antenna, we provide a slab 16 of molded powdered iron, which is secured to the inside of door 12 in such a manner that it lies within the central turn of the loop antenna 14 whenever the latter is in its folded position, as indicated in dotted lines in Fig. 1 and in full lines in Fig. 3. This location of the slab 16 means that it has substantially no effect upon the inductance of the loop when the latter is in the full line position of Fig. 1, but it operates to increase the inductance of the loop whenever the latter is folded down into the dotted line position of Fig. 1, as it must be to be received within the cabinet 10.

When the door and the loop are folded into the cabinet 10, occupying the position shown in Fig. 3, the proximity of metal parts thereto tends to decrease the loop inductance due to the effects mentioned above. Now, however, the presence of slab 16 within the loop increases its inductance

as compared with the antenna in free space, and by proper selection of the permeability, shape, size and position of such slab, the increase in inductance due thereto can be made precisely equal to the decrease resulting from the antenna's being folded into the cabinet.

We have found that a molded slab of low-loss powdered iron, approximately $\frac{3}{2}$ to $\frac{1}{2}$ inch in thickness, and so located on door 12 as to lie in or very near and parallel to the plane of the folded loop, is satisfactory to perform the compensation required in average installations. It is preferred to make the slab somewhat smaller than the dimensions of the innermost turn of the loop, so that its position may be varied somewhat in its own plane. Such an adjustment permits small production variations in antenna inductance to be taken care of, since a movement of the slab from an exactly centered position to a position closer to part of the inside loop turn will increase the degree of compensation effected.

It is important that the iron slab be so located that none of the turns of the antenna cross the surface of the iron, since this would increase the distributed capacitance of the loop, and the antenna circuit would not track or stay in resonance at the high frequency end of the tuning band.

In the event that the inside turn of the loop 14 is of relatively large diameter, compensation may be effected with a minimum of inductive material by forming the slab as a hollow ring shaped to fit within the inside turn of the loop, with the core of the slab empty of material. This modification is illustrated in Fig. 4, wherein 18 designates a loop antenna having a large inside turn area, and 20 designates the slab of powdered iron having a hollow center portion.

Any convenient means may be employed to secure the compensating slab in place on the door 12. In Figs. 2 and 4 I have shown the slabs as having a pair of apertures adapted to receive screws 24 threaded into the door material, and provided with oversize washers 26 permitting the slabs to be moved about somewhat for adjustment purposes, yet readily clamped down to secure the slabs in adjusted position. Numeral 23 in Fig. 1 represents an insulating bushing surrounding the screws 24 and adapted to maintain the plane of the slab in the plane of the folded loop. However, any equivalent means for mounting the antenna compensating slab may be utilized, so long as the above conditions as to relative positions are satisfied.

As compared with prior art methods of loop antenna compensation, it will be observed that our system is simpler and hence more economical to provide in production, since it involves the addition of only one major part which has no electrical connections with the antenna or the set chassis. At the same time, minor adjustments to take care of production variations, both in antennas and in iron slabs, are readily accomplished. Furthermore, in its open position, the "Q" of the antenna according to our invention is unaffected by the presence of the compensating means, while in its closed position the change in "Q" can be made negligible, or may even be in-

creased by the use of iron having high permeability and high "Q."

It is obvious that many changes and modifications can be made in the details and arrangements of our invention without departing from the spirit thereof; in particular, we wish to point out that it is not essential that the compensating slug lie in the plane of the loop, although this is a convenient arrangement when the slug is smaller than the inside turn of the loop. It is, however, desirable to have the plane of the slug parallel and as close as possible to the plane of the loop, particularly when a large change of inductance must be compensated. We intend to claim as our invention all these and other modifications of the invention which come within the scope of the appended claims.

We claim:

1. In combination with a loop antenna of the type mounted for movement on a support between two operative positions in which its inductance is different, compensating means comprising a slab of magnetic material secured to said support in such a position as to lie substantially within the turns of said loop antenna when the latter is in one of its operative positions.
2. The invention in accordance with claim 1, and means for adjusting the position of said slab with respect to said support.
3. In radio equipment of the type comprising a cabinet, circuit components in said cabinet, a hinged closure for said cabinet, and a substantially planar loop antenna mounted on said closure for movement between positions parallel to said closure and perpendicular thereto, the improvement which comprises a member of relatively high magnetic permeability secured to said closure in position to enter the magnetic field of said antenna when the latter is moved to its position parallel to said closure, whereby to compensate for variations of inductance of said antenna as the latter is moved from its perpendicular position to its parallel position.
4. The invention in accordance with claim 3, in which said antenna is hingedly connected to said closure along an axis relatively spaced from the axis of rotation of said closure with reference to said cabinet.
